UNITED STATES PATENT OFFICE

EVERETT WORTHINGTON, OF CHICAGO, ILLINOIS, ASSIGNOR TO THE STROMBERG-CARLSON TELEPHONE MANUFACTURING COMPANY, OF ROCHESTER, NEW YORK, A CORPORATION OF NEW YORK

DESIGN FOR A RADIOCABINET OR SIMILAR ARTICLE

Application filed October 24, 1929. Serial No. 33,154. Term of patent 3½ years.

To all whom it may concern:

Be it known that I, EVERETT WORTHINGTON, a citizen of the United States, residing at Chicago, county of Cook, State of Illinois, have invented a new, original, and ornamental Design for Radiocabinets or Similar Articles, of which the following is the specification, reference being had to the accompanying drawing, forming a part thereof.

Figure 1 is a perspective view of a por-

tion of a cabinet showing my new design, the doors of the cabinet being shown closed while Figure 2 is a perspective view of the same cabinet with the doors thereof in open position.

I claim:

The ornamental design for a radio cabinet or similar article as shown.

EVERETT WORTHINGTON.
